UNITED STATES PATENT OFFICE.

HENRY W. MERRITT, OF SYRACUSE, NEW YORK, ASSIGNOR TO THE MONARCH TYPEWRITER COMPANY, OF SYRACUSE, NEW YORK, A CORPORATION OF NEW YORK.

TYPE-WRITING MACHINE.

No. 891,849.

Specification of Letters Patent.

Patented June 30, 1908.

Application filed October 16, 1905. Serial No. 283,004.

To all whom it may concern:

Be it known that I, HENRY W. MERRITT, citizen of the United States, and resident of Syracuse, in the county of Onondaga and State of New York, have invented certain new and useful Improvements in Type-Writing Machines, of which the following is a specification.

My invention relates more particularly to the ribbon mechanism of that class of type-writing machines employing a ribbon vibrator or carrier, which terms, as used herein, comprehend any device operable by the printing keys for moving the ribbon to cover and uncover the printing point.

One object of my invention is to provide an improved construction wherein a ribbon having a plurality of fields of different characteristics may, under the influence of a printing key, be moved to cover the printing point with any desired field of the ribbon.

Another object is to provide means to dispense at will with the crosswise feed of the ribbon in that class of machines employing a ribbon vibrator and wherein the ribbon has both a crosswise and a lengthwise feed.

An additional object is to provide means for enabling a ribbon of more than one color to be used in the last named class of machines.

Other objects will appear in the course of the following specification.

To the above ends the invention consists in the features of construction, combinations of devices and arrangements of parts to be hereinafter more fully described and particularly pointed out in the claims.

In the accompanying drawings, Figure 1 is a vertical longitudinal sectional view of a typewriting machine embodying my invention, certain parts of the machine being omitted. Fig. 2 is an enlarged detail view of a part of the ribbon mechanism. Fig. 3 is a front elevation of the machine showing the keyboard sectioned away, parts of the machine being omitted and other parts being broken away for the sake of clearness. Fig. 4 is an enlarged fragmentary side elevation of parts of the ribbon mechanism, certain parts being shown in section. Fig. 5 is a rear elevation of the parts shown in Fig. 4. Fig. 6 is a view corresponding to Fig. 4 but showing certain of the parts in different relations from those in which they appear in said Fig.

4. Fig. 7 is a rear elevation of the parts 55 shown in Fig. 6.

My invention is shown as embodied in a Monarch typewriting machine, but it is to be understood that it may be adapted to other forms of writing machines.

In the drawings, 1 is the base of the machine supporting corner posts 2 which sustain a top plate 3. Key levers 4 are fulcrumed on a fulcrum plate 5 and each key lever is provided with a restoring spring 6. 65 Pivoted at 7 to each key lever is a sub-lever 8, the lower portion whereof coacts with a fixed abutment 9 and the upper end whereof is connected by a link 10 with a type bar 11. Each type bar is pivotally mounted in a 70 hanger 12 which is one of a series of hangers arranged in a segment of a circle on a segmental type bar support 13. The type bars are normally supported at their outer ends by a segmental type rest 14 and said bars are 75 adapted to coöperate with a platen 15 mounted in a carriage 16, said carriage being guided and supported by anti-friction balls 17 which coöperate with grooved rails 18 on the carriage and with oppositely grooved 80 rails 19 secured to brackets 20 fixed to the top plate of the machine. A feed rack 21 is mounted on the carriage and normally meshes with a feed pinion 22, the latter being operatively connected with an escapement 85 wheel 23.

Adapted to coöperate with the escapement wheel are feed dogs 24 at the top of a pivoted dog rocker 25, said dog rocker having a horizontally disposed arm 26 which is connected 90 by a link 27 with a universal bar frame 28, the latter being pivoted in the base of the machine at 29. The frame 28 carries a universal bar 30 which extends from side to side of the machine beneath the series of key levers 4 and the spacing levers (not shown) and is adapted to be actuated by said levers when they are depressed during printing or spacing operations. The carriage 16 is connected by a band 31 with a spring drum 32 100 which tends constantly to draw the carriage across the machine to the left, so that when the universal bar 30 is operated the escapement mechanism just described is caused to be actuated in a known manner to permit of 105 letter space movements of the carriage.

Ribbon spools 33, arranged above the top plate 3 at each side of the machine and for-

wardly of the platen, receive a ribbon 34 which, as herein shown, is divided longitudinally into stripes or fields *a* and *b* of different characteristics; for example, the field *a* may be of one color such as black and the field *b* of a different color, as red, or the field *a* may be copying ribbon and the field *b* record ribbon. The ribbon 34 may be fed longitudinally from either spool to the other by any suitable means, that illustrated in the drawings having the general characteristics of the ribbon feeding mechanism of the Monarch machine. Each ribbon spool 33 is carried by and turns with an upright shaft 35 which rotates in a fixed bearing 36 and has secured at its lower end a small beveled gear 37. The gear 37 meshes with a beveled pinion 38 secured to the forward end of a horizontal shaft 39, which shaft carries at its rear end a beveled pinion 40, the latter being adapted to mesh with a beveled driving pinion 41 mounted on a driving or power shaft 42, having its bearings in lugs 43 depending from the top plate. Rotary movement is transmitted to the shaft 42 through beveled pinions 44 and 45, the pinion 44 being operatively connected with the driving shaft and the pinion 45 being operatively connected with the spring drum 32. It will be understood that each ribbon spool 30 is connected with a gear train like that above described, each of said gear trains being adapted to be actuated from a driving pinion 41 on the driving shaft 42. It will further be understood that the driving shaft 42 is capable of longitudinal movement and that the longitudinal position of said shaft determines which driving pinion 41 will be in mesh with its cooperating pinion 40 and which ribbon spool will be turned to wind the ribbon thereon.

Midway between the ribbon spools, the ribbon 34 is threaded through a ribbon vibrator or carrier 46 which is guided and supported in the upright arms 47 of a bracket 48, the latter being secured to the top plate by screws 49. The lower portion of the vibrator 46 is bifurcated and provided with a cross pin 50 bridging the bifurcation, said pin being engaged by the slotted forward end of an operating lever 51 pivoted at 52 in a lug 53 depending from the under side of the top plate. The rear arm of the operating lever 51 is formed with an elongated slot 54 and engaging with this slot is a pin or stud 55 secured to the top of a link 56, the lower end of said link being pivoted at 57 to the universal bar frame 28. Near its upper end the link 56 is provided with a forwardly and downwardly bent arm 58.

The link 56 is adapted to be swung about its pivot 57 in order to cause the stud 55 to move longitudinally in the slot 54 so as to engage the operating lever 51 at varying distances from its pivot or fulcrum 52 and thereby to vary the throw of the ribbon car-

rier or vibrator 46. This swinging or vibratory movement of the link 56 is caused by an eccentric member 59 which is slidably mounted on the driving shaft 42 and which is adapted to coöperate with the strap formed by the link 56 and its bent arm 58. The eccentric member 59 comprises a narrow eccentric working face 60, a tapered or cam portion 61 and a sleeve portion 62, the latter being formed with a circumferential groove or depression 63. A screw 64 passes into the sleeve portion 62 of the member 59 and enters an elongated slot or groove 65 in the driving shaft 42 (Fig. 3). The eccentric member 59 is thereby slidably connected with the driving shaft 42 and is caused to rotate with said shaft, but may be moved longitudinally of the shaft without affecting the latter. The shaft 42 may also be moved longitudinally without affecting the eccentric member 59. The longitudinal movement of the member 59 is controlled by a switching member which is here shown as an arm 66 having a fork 67 at its lower end and a collar portion 68 at its upper end. The fork 67 at the lower end of the switching member 66 embraces or partially surrounds the depression 63 in the eccentric member 59. The eccentric member 59 is adapted to be slid longitudinally of the shaft 42 and into and out of coöperative engagement with the link 56 by means of the switching member 66, the collar portion 68 of which is secured to the inner end of a slide rod 69 by a set screw 70. The slide rod 69 has its bearings in the right-hand lug 43 of the ribbon driving shaft and in a right-angled bracket 71 which is secured to the under side of the top plate by a screw 72. Secured by a set screw 73 on the slide rod 69 to the right of the member 66 (or to the left thereof when viewed from the rear as in Figs. 5 and 7), is a collar 74 having a circular face 74^a and a tapered or cam face 75. The faces or surfaces 74^a and 75 of the member 74 are adapted to coöperate with a horizontally disposed arm 76 projecting from the right-hand end of a rock shaft 77 mounted to turn in the depending bearing arms 78 of a U-shaped bracket 79 which is made fast to the under side of the top plate by headed screws 80. The left-hand end of the rock shaft 77 (or the right-hand end, viewed from the rear as in Figs. 5 and 7) has secured to it outside the bearing 78 a depending crank arm 81, the lower end whereof is preferably provided with a small grooved wheel or roller 82 which is adapted to coöperate with the rear edge of the link 56. A coiled spring 83 (Fig. 1) has one end secured to the link 56 and the other end to the link 27 of the carriage feeding mechanism, and said spring tends constantly to draw the link 56 rearwardly away from the fulcrum 52 of the operating lever 51. The outer or right-hand end of the slide rod 69 is provided with a collar 84 carrying

a pin 85, which is embraced by the fork of a bifurcated crank arm 86 fixedly secured to the rear end of a horizontally disposed and forwardly extending rock shaft 87 (Figs. 2 and 3). The rock shaft 87 extends through and terminates slightly in front of the front plate 88 of the machine. A crank arm 90 is secured by a headed screw 89 to the front end of the rock shaft 87 and is provided with a finger piece or handle 91 and terminates at its free end in a pointer 92, said pointer being adapted to coöperate with indicating marks (as the letters N, B and R) formed preferably on the front face of the plate 88. The rock shaft 87 has its bearings in bearing plates 93 which are secured to lugs 94 which bear the right-hand ribbon feeding shaft 39, said bearing plates being fixed in place by headed screws 95. A collar 96 is secured to the rock shaft 87 and abuts against the rear face of the forward bearing plate 93, and integral with said collar is a positioning member 97 which, as herein shown, is in the form of sectoral plate extending to the left and down-
wardly from the rock shaft 87 and having its periphery formed with depressions or notches 98, 99, 100 (Fig. 2). A detent or locking spring 101 is fixedly secured to the under side of the top plate in any suitable manner and is adapted to engage the depressions or notches in the positioning member 97.

The operation of the mechanism above described will now be briefly explained. Suppose that the parts be positioned as indicated in Figs. 1, 2 and 3 with the indicator or pointer 92 pointing to the indicating mark N (which means "normal") on the front plate 88, the sectoral positioning member 97 will be engaged by the detent 101 and the slide rod 69 will be in its extreme left-hand position with the positioning member 66 causing an engagement or coöperation between the eccentric face 60 of the member 59 and the strap in the link 56. When the parts are so arranged the rock shaft 77 and the crank arms 76 and 81 will, during part of the time, be maintained by gravity in the positions indicated in Figs. 1 and 3, with the crank arm 81 in a substantially vertical position and the crank arm 76 in a substantially horizontal position. During the operation of the machine, however, the rotation of the eccentric face 60 moves the link 56 progressively towards and away from the fulcrum 52 and will sometimes swing the link 56 far enough rearwardly to cause it to engage with the roller 82 to swing the arm 81 rearwardly to rock the rock shaft 77 and bring the arm 76 very close to the slide rod 69. With the positioning mechanism arranged as now being considered, the ribbon will be fed longitudinally and will also be given a variable crosswise feed, so that the type impressions will follow a serpentine or

wavy path lengthwise of the ribbon and extending from side to side thereof as is characteristic of the ribbon feed of the Monarch machine. If a ribbon of uniform character be in place in the machine, a ribbon having a plurality of fields of different characteristics, such as the ribbon 34, may be substituted for the uniform ribbon in a known manner. Should the mechanism still be allowed to remain in the relations indicated in Figs. 1-3, inclusive, some of the type impressions will now be printed, say in black, others in red, and others partly in black and partly in red, giving a variegated or parti-colored effect which is sometimes desirable in ornamental typewriting. Usually, however, it is desired to print all the letters of a word or a succession of words in one color.

If it first be desired to print in black alone, the handle 91 is pressed to the right until the pointer 92 points to the letter B (indicating "black") on the front plate 88. By this movement the rock shaft 87 is rotated rightward and the notch 99 in the sectoral plate is engaged by the detent 101. At the same time the slide rod 69 is slid rightward in its bearings, causing the member 66 to act on the eccentric member 59 to move the latter rightward along the driving shaft 42 to the position indicated in Figs. 4 and 5, which latter view, it will be recalled, is a rear view. It will be noted that by this movement the eccentric face 60 is disengaged from the strap in the link 56, whereupon the latter is swung rearwardly by spring 83, carrying with it the crank arm 81. The rearward movement of the link 56 continues until the rotation of the rock shaft 77 by the crank arm 81 brings the crank arm 76 into contact with the sliding rod 69, thereby preventing further movement of the crank arm 81 and the link 56. During subsequent printing operations the link 56 will be maintained with the stud 55 at the rear of the slot 54 in the operating lever 51 and as far as possible from the fulcrum 52 of said lever. The link 56 as it moves up and down has a bearing on the roller 82 at the end of the crank arm 81. The parts are so arranged and proportioned that with the stud 55 maintained at the rear of the slot 54, the operating lever will have a constant throw and the ribbon vibrator will be moved thereby so as to cause the field *a* or the black field to cover the printing point on the platen. The path of the type impressions will be in a straight line longitudinal of said field *a*. It will be noted from an inspection of Fig. 5 that the described sliding movement of the rod 69 has served to bring the cam member 74 close to but not actually in engagement with the crank arm 76. It will further be seen from an inspection of said figure that endwise movement of the rock shaft 77 in either direction is

4
prevented by the contact of the crank arms 76 and 81 with the bearing arms 78 of the bracket 79.

If it be desired to print upon the red field 5 of the ribbon, the finger piece 91 is pushed still further to the right until the pointer 92 registers with the letter R (meaning "red") inscribed on the front plate 88 to the right of the letter B. This movement causes a 10 further rotary movement of the rock shaft 87 and brings the notch 100 in the positioning plate 97 into engagement with the detent 101, while at the same time the slide rod 69 is moved still further to the right, causing the 15 slide or positioning member 66 to slide the eccentric member 59 to the position indicated in Fig. 7, while at the same time the cam face 75 of the member 74 contacts with the crank arm 76 and raises the latter to the 20 circular face 75^a, rocking the rock shaft 77 and swinging the crank arm 81 forward. As the crank arm 81 is swung forwardly it 25 pushes the link 56 longitudinally of the lever 51 against the force of the spring 83 and causes the stud 55 to engage the slot 54 near its forward end and close to the fulcrum 52 of the operating lever. The parts will now 30 be positioned as indicated in Figs. 6 and 7, and during the operation of the machine the link 56 will be moved up and down against the roller 82, and the position of the stud 55 in respect to the fulcrum 52 will not vary 35 appreciably. Consequently the throw communicated to the ribbon vibrator by the operating lever 51 will be a constant one, and the parts are so proportioned and adjusted that this constant throw will cause the field b or red field of the ribbon to always be brought to the printing point. The path of the type 40 impressions will follow a straight line longitudinal of said red field b.

By reversing the operations above described the black field or the entire surface of the ribbon may again be brought into play as 45 desired.

It will be noted that in my improved construction of ribbon feeding mechanism I employ a single operating lever and a single link which is in constant engagement with said 50 lever; that the link is moved longitudinally of the lever by both the eccentric member 59 and the member comprising the rock shaft 77 and the crank arms 76 and 81, which last member is in effect a bell crank lever comprising arms 76 and 81 and an elongated pivot 77; that the bell crank member positions the link 56 independently of the member 59, said bell crank member being inoperative when the eccentric member 59 is operative, and operative when said eccentric member is inoperative.

By my invention I provide devices of simplified and improved construction for performing the various functions hereinbefore

set forth and it is to be understood that 65 various changes may be made without departing from the spirit and scope of my invention.

What I claim as new and desire to secure by Letters Patent, is:—

1. In a typewriting machine, the combination of a ribbon vibrator; a single lever for operating the same; a link; means for causing said link to operate automatically upon said lever at progressively increasing 75 and decreasing distances from the fulcrum of said lever; means for throwing said automatic means out of operation; a cam operable by said last recited means; and means operable by said cam for positioning said link longitudinally of said lever independently of said automatic means.

2. In a typewriting machine, the combination of a ribbon vibrator; a single lever for operating the same; a link; means for 85 causing said link to operate automatically upon said lever at progressively increasing and decreasing distances from the fulcrum of said lever; means for throwing said automatic means out of operation; a cam operable by said last recited means; and means operable by said cam for positioning said link longitudinally of said lever, said last named means being operative when said 90 automatic means is inoperative.

3. In a typewriting machine, the combination of a ribbon vibrator; a single lever for operating said vibrator; a link; means for causing said link to operate automatically upon said lever at progressively increasing 100 and decreasing distances from the fulcrum of said lever; hand actuated means for throwing out of operative relation said automatic means; a spring constantly tending to draw said link away from the fulcrum of said lever; a cam operable by said hand actuated means; and means operable on said link to force it towards the fulcrum of said lever against said spring, said last named means being operative when said automatic means 105 is inoperative.

4. In a typewriting machine, the combination of a ribbon vibrator; a single lever for operating said vibrator; a link; means for causing said link to operate automatically 115 upon said lever at progressively increasing and decreasing distances from the fulcrum of said lever; hand actuated means for throwing out of operative relation said automatic means; a spring operable to draw said link away from the fulcrum of said lever; a cam operable by said hand actuated means; and means operable by said cam to force said link towards the fulcrum of said lever.

5. In a typewriting machine, the combination of a ribbon vibrator; a single operating lever therefor; a single link adapted to actuate said lever; an eccentric member

- adapted to control the position of said link longitudinally of said lever; hand actuated means for controlling said eccentric member; a rock shaft operable by said hand actuated means; and means operable by said rock shaft to position said link longitudinally of said lever when said eccentric member is inoperative. 65
6. In a typewriting machine, the combination of a ribbon vibrator; an operating lever therefor; an actuating link for actuating said lever and moving said vibrator to and from the printing point; a rock shaft; hand actuated means operative to rock said shaft; and means operative by said rock shaft for positioning said link longitudinally of said lever to vary the length of the lever arm. 70
7. In a typewriting machine, the combination of a ribbon vibrator; an operating lever therefor; a link adapted to actuate said lever; an eccentric adapted to control the position of said link longitudinally of said lever; hand actuated means for rendering said eccentric inoperative; a rock shaft operative by said hand actuated means; and a crank arm operative by said rock shaft to move said link longitudinally of said lever when said eccentric is inoperative. 75
8. In a typewriting machine, the combination of a ribbon vibrator; an operating lever therefor; a link adapted to actuate said lever; an eccentric adapted to control the position of said link longitudinally of said lever; hand actuated means for rendering said eccentric inoperative; a cam operative by said hand actuated means; a rock shaft; a crank arm on said rock shaft operated by said cam; and a second crank arm on said rock shaft adapted, when said rock shaft is rocked by said cam, to move said link longitudinally of said lever. 80
9. In a typewriting machine, the combination of a ribbon vibrator; an operating lever therefor; a key actuated universal bar; a link operated thereby to actuate said lever; an eccentric for automatically moving said link progressive distances longitudinally of said lever; a hand actuated slide rod operative on said eccentric to render it inoperative; a cam on said slide rod; a rock shaft operable by said cam; and a crank arm on said rock shaft adapted to move said link longitudinally of said lever. 85
10. In a typewriting machine, the combination of a ribbon vibrator; an operating lever; a key actuated universal bar; a link engaging said lever and operative by said universal bar; a spring constantly tending to draw said link away from the fulcrum of said lever; an eccentric adapted to move said link automatically progressive distances longitudinally of said lever; a hand actuated slide rod adapted to render said eccentric inoperative; a cam on said slide rod; a rock shaft operable by said cam; and a crank arm on said rock shaft adapted to move said link against the force exerted by said spring. 90
11. In a typewriting machine, the combination of a ribbon vibrator; an operating lever; a key actuated universal bar; a link connected therewith and with said operating lever; an eccentric automatically operative on said link to move it progressive distances longitudinally of said lever; a hand actuated slide rod adapted to render said eccentric inoperative; a cam on said slide rod; and a bell crank lever one of the arms whereof is adapted to be operated by said cam and the other arm whereof is operable on said link. 95
12. In a typewriting machine, the combination of a ribbon vibrator; an operating lever therefor; a link for actuating said lever; an eccentric for moving said link longitudinally of said lever; hand actuated means for rendering said eccentric inoperative; a cam operable by said hand actuated means; and a bell crank lever operable by said cam and operative on said link to move it longitudinally of said lever when said eccentric is inoperative. 100
13. In a typewriting machine, the combination of a ribbon vibrator; an operating lever; an actuating link therefor; a strap on said link; an eccentric adapted to coöperate with said strap; a slide rod operative on said eccentric; a cam on said slide rod; a bell crank lever operated by said cam and operable on said link; a rock shaft operative on said slide rod; and a finger piece on said rock shaft. 105
14. In a typewriting machine, the combination of a ribbon vibrator; an operating lever; an actuating link therefor; a strap on said link; an eccentric adapted to coöperate with said strap; a slide rod operative on said eccentric; a cam on said slide rod; a bell crank lever operative by said cam and operable on said link; a rock shaft operative on said slide rod; a crank arm on said rock shaft at the front of the machine, said crank arm being provided with a handle and with a pointer; and an indicating device with which said pointer is adapted to coöperate. 110
15. In a typewriting machine, the combination of a ribbon vibrator; an operating lever; an actuating link therefor; a strap on said link; an eccentric adapted to coöperate with said strap; a slide rod operative on said eccentric; a cam on said slide rod; a bell crank lever operative by said cam and operable on said link; a rock shaft operative on said slide rod; a sectoral positioning plate on said rock shaft; and a spring detent adapted to coöperate therewith to maintain said rock shaft in any one of a plurality of predetermined positions. 115
16. In a typewriting machine, the combination of a ribbon vibrator; an operating lever

therefor; an actuating link for actuating said lever and moving said vibrator to and from the printing point; a bell crank lever; and hand actuated means operative to vibrate said bell crank lever, said bell crank lever being operative to move said link longitudinally of said operating lever in one direction; and a spring constantly tending to move said link in the opposite direction.

5 17. In a typewriting machine, the combination of a ribbon vibrator; an operating lever therefor; an actuating link for said lever; a bell crank lever; hand actuated means operative to vibrate said bell crank lever, said

bell crank lever being operative to move said link longitudinally of said operating lever in 15 one direction; and a spring constantly tending to move said link in the opposite direction.

Signed at Syracuse, in the county of Onondaga and State of New York, this 13th 20 day of October A. D. 1905.

HENRY W. MERRITT.
